UNITED STATES PATENT OFFICE.

NORMAN W. LITTLEJOHN, OF NEOSHO, MISSOURI, ASSIGNOR OF ONE-HALF TO
SAMUEL A. KENOYER, OF MIAMI, OKLAHOMA.

JACK.

Application filed January 14, 1925. Serial No. 2,423.

To all whom it may concern:

Be it known that I, NORMAN W. LITTLEJOHN, a citizen of the United States, residing at Neosho, in the county of Newton and State of Missouri, have invented certain new and useful Improvements in Jacks, of which the following is a specification.

This invention relates to jacks, and more particularly to mechanically operated jacks.

An object of the invention is the provision of a jack that may be raised or lowered with the same motion of the handle and which does not require the reversal of the pawls when the lifting member is to be moved in a reverse direction.

In the present invention, I provide a pair of pawls adapted to function as a holding pawl and a lifting pawl when the handle is moved through a predetermined arc, and I further provide a latch cooperating with the two pawls which automatically functions to release the pawls when the handle is moved through a second arc and thus permit the jack to be lowered.

In the accompanying drawings, I have shown one embodiment of the invention. In this showing:

Figure 1 is a side elevation,

Figure 2 is a plan view,

Figure 3 is a detail sectional view on line 3-3 of Figure 1,

Figure 4 is a vertical sectional view showing the pawls and the latch,

Figure 5 is a diagrammatic illustration of the pawls and latch,

Figure 6 is a horizontal sectional view on line 6-6 of Figure 4,

Figure 7 is a similar view on line 7-7 of Figure 4, and,

Figure 8 is a similar view on line 8-8 of Figure 4.

Referring to the drawings, the reference numeral 1 designates a suitable base on which the jack is mounted. An upright casing 2 is arranged on the base. As shown, the casing is substantially U-shaped (see Figures 6 to 8) and is open at the rear. The front of the casing is provided with a slot 3 extending from a point above the base to the top. Adjacent the top of the casing, the side walls are provided with extensions 4 in which the operating mechanism is mounted. A plunger 5 is mounted in the casing and provided with rack teeth 6 on

its rear face. The upper end of the plunger is provided with a seat or rest 7 for the reception of a portion of the axle or other part of the motor vehicle to be lifted. To permit the use of the jack with vehicles equipped with balloon tires, an auxiliary member 8 is secured to the front of the plunger through the slot 3. As shown, the auxiliary member may be fastened to the plunger by means of screws 9 or other suitable fastening elements and the adjacent face of the auxiliary member may be provided with lugs or projections 10, adapted to be received in corresponding openings or recesses in the face of the plunger. The side walls of the casing are provided with inwardly extending ribs 12, adapted to form a guide for the plunger.

A gear or pinion 13 is mounted on a pivot pin 14 arranged between the extensions 4 and is provided with teeth 15 meshing with the rack teeth 6 of the plunger. As shown (see Figure 6), the gear is substantially equal in width to the space between the ribs 12. A handle 16 is also mounted on the pivot pin 14, the handle being bifurcated at its inner end and being provided with arms 17 extending on each side of the gear between the gear and the adjacent extension 4 (see Figure 6). A main lifting pawl 17 is pivotally mounted on a pin 18 arranged in the bifurcated portion of the handle. The lower end of the pawl is provided with a tooth 18 adapted to engage between the teeth 15 of the gear. The pawl is provided with a curved face 19 and is provided with a pointed end 20 arranged opposite the tooth 18. The upper end of the pawl is extended, as at 21, forming a counter-balancing member.

A latch 22 is also pivotally mounted on the handle, the latch being carried by a pivot pin 23 and the latch is provided with a substantially straight front face 24, having a tooth 25 at its lower end. This tooth is adapted to engage a projection 26 formed on the rear end of the main lifting pawl.

The jack is further provided with a holding pawl 27 which is pivotally mounted on a pin 28 arranged in the extensions 4 beneath the gear. The inner end of the pawl is provided with a tooth 29 which is adapted to engage between the teeth of the gear by gravity. Beyond the pivot, the pawl is pro-

vided with a substantially arcuate extension 30 having a tooth 31 formed on its rear end.

As shown in Figures 1 to 3 of the drawings, the handle 16 may be hollow and suitable extensions 32 may be secured therein by means of fastening elements 33.

The upper ends of the extensions 4 are provided with rearwardly extending arms 34, adapted to receive a pin 35 which carries a roller 36.

In the lifting operation of the jack, the handle is swung through the arc from the full line position shown in Figure 1 of the drawings, to the dotted line position. During this operation, the latch 22 is inoperative. As the jack is raised from the position shown in full lines, the latch tooth 25 is disengaged from the tooth on the holding pawl 27 and the holding pawl swings by gravity to the dotted line position with the tooth 29 in engagement with the gear. This holds the plunger in a set position until the lifting pawl begins to function. After the handle has reached the dotted line position, it is moved downwardly. Due to the counterbalance 21, the tooth 18 of the lifting pawl engages between two of the teeth of the gear and when the handle is moved downwardly, the gear is revolved in a clockwise direction, lifting the plunger. This action is repeated until the plunger has been raised the desired amount.

In lowering the plunger, the handle is swung from the position shown in full lines in Figure 4 of the drawings to the position shown in dotted lines. With the parts in the full line position, the upper surface of the lifting pawl has engaged the roller 36 to swing the lifting pawl on its pivot and cause the teeth 25 and 26 to engage each other. The lifting tooth 18 is thus locked in an inoperative position and as the handle is swung downwardly, no further lifting takes place. As the handle approaches the dotted line position, the rear end of the holding pawl forces the latch from engagement with the lifting pawl and on further downward movement, the latch engages the holding pawl. When the handle is then swung upwardly, the holding pawl is released from the gear, which permits the plunger to lower under weight of the load. As the handle approaches its upper limit, the latch again engages the lifting pawl and the holding pawl being free to swing, assumes an operative position. Thus a step by step downward movement is obtained by merely increasing the arc through which the handle is swung and without manually reversing any pawls or other operating parts on the jack.

It is to be understood that the form of my invention herewith shown and described is to be taken as a preferred example of the same, and that various changes in the shape,

size, and arrangement of parts may be resorted to without departing from the spirit of the invention or the scope of the subjoined claims.

I claim:

1. In a lifting jack, a casing, a plunger mounted in said casing, said plunger being provided with rack teeth, a gear rotatably mounted in said casing and meshing with said teeth, a handle pivotally mounted on said casing, a lifting pawl carried by said handle, a holding pawl pivotally mounted on said casing, means carried by said casing and adapted to engage said lifting pawl when the handle is moved in a given direction to move said lifting pawl to an inoperative position, and an automatically releasable latch adapted to engage said lifting pawl to retain it in inoperative position when the handle is moved in the opposite direction.

2. A device constructed in accordance with claim 1 wherein said holding pawl is adapted to release said lifting pawl from said latch when the handle is moved a predetermined distance in said last named direction.

3. A device constructed in accordance with claim 1 wherein said holding pawl is adapted to release said lifting pawl from said latch when the handle is moved a predetermined distance in said last named direction, and said latch is then adapted to engage said holding pawl whereby said plunger will be lowered with a step by step movement.

4. In a lifting jack, a casing, a plunger mounted in said casing, said plunger being provided with rack teeth, a gear rotatably mounted in said casing and meshing with said teeth, a handle pivotally mounted on said casing, a lifting pawl carried by said handle, a holding pawl pivotally mounted on said casing, means for swinging said lifting pawl to an inoperative position when the handle is moved in one direction, and means for locking said lifting pawl in inoperative position when said handle is moving in the opposite direction.

5. In a lifting jack, a casing, a plunger mounted in said casing, said plunger being provided with rack teeth, a gear rotatably mounted in said casing and meshing with said teeth, a handle pivotally mounted on said casing, a lifting pawl carried by said handle, a holding pawl pivotally mounted on said casing, a roller mounted on said casing and adapted to engage said lifting pawl when the handle is moved in a given direction to move said lifting pawl to an inoperative position, and an automatically releasable latch adapted to engage said lifting pawl.

6. A device constructed in accordance with claim 5 wherein said holding pawl is

adapted to release said lifting pawl from said latch when the handle is moved in the opposite direction.

7. A device constructed in accordance with claim 5 wherein said holding pawl is adapted to release said lifting pawl from said latch when the handle is moved in the opposite direction, and said latch is then adapted to engage said holding pawl where-
10 by said plunger will be lowered with a step by step movement.

8. In a lifting jack, a casing, a plunger mounted in said casing, said plunger being provided with rack teeth, a gear rotatably mounted in said casing and meshing with said teeth, a handle pivotally mounted on said casing, a lifting pawl carried by said handle, a holding pawl pivotally mounted on said casing, a rearwardly extending mem-
15 ber at the top of said casing adapted to contact with the upper end of said lifting pawl in its full upward movement to release said lifting pawl from mesh with said gear, and an automatically releasable latch loosely mounted on said handle and adapted to en-
20 gage said lifting pawl in its inoperative position.

9. In a lifting jack, a casing, a plunger mounted in said casing, said plunger being provided with rack teeth, a gear rotatably mounted in said casing and meshing with said teeth, a handle pivotally mounted on said casing, a lifting pawl carried by said handle, a holding pawl pivotally mounted on said casing, a rearwardly extending mem-
25 ber at the top of said casing, a roller mount-
30 ed at the outer end of said member and adapted to contact with said lifting pawl to move said lifting pawl to an inoperative position, and a latch loosely mounted on said handle to hold said lifting pawl in in-
35 operative position, said holding pawl being adapted to release said lifting pawl from

said latch when said handle is moved in an opposite direction.

10. In a lifting jack, a casing, a plunger mounted in said casing, said plunger being provided with rack teeth, a gear rotatably mounted in said casing and meshing with said teeth, a handle pivotally mounted on said casing, a lifting pawl carried by said handle, a holding pawl pivotally mounted on said casing, a rearwardly extending member at the top of said casing, a roller mounted at the outer end of said member and adapted to contact with said lifting pawl to move said lifting pawl to an inoperative position, and a latch loosely mounted on said handle to hold said lifting pawl in inoperative position, said holding pawl being adapted to release said lifting pawl from said latch when said handle is moved in an opposite direction, and said latch being then adapted to engage said holding pawl whereby said plunger will be lowered with a step by step movement.

11. In a lifting jack, a support, a lift bar slidably connected to said support, said lift bar being provided with rack teeth, a gear meshing with said teeth, a fixed pivot pin connected between said gear and said support, a handle pivotally connected adjacent one end of said pivot pin, a lifting pawl pivotally connected to said handle, a holding pawl pivotally mounted on said support, means carried by said support adjacent the top thereof for contacting with said lifting pawl to release it from engagement with said gear, and a latch pivotally connected to said handle and adapted to engage said lift-
75 ing pawl to retain it in inoperative position when said handle is moving in one direc-
80 tion.

In testimony whereof, I affix my signature.

NORMAN W. LITTLEJOHN.
